UNITED STATES PATENT OFFICE.

JOHN G. WYNN, OF MADISON, WISCONSIN, ASSIGNOR TO THE ZENO BUTTON COMPANY,
OF INDIANAPOLIS, INDIANA, A CORPORATION.

CASING FOR COIN-CONTROLLED APPARATUS.

Original application filed August 27, 1924, Serial No. 734,373. Divided and this application filed June 25, 1925. Serial No. 39,462.

This application is divisional of my prior application on vending machine, Serial No. 734,373, filed August 27, 1924.

The present invention is designed for use 5 in connection with a button vending machine, adapted upon the insertion of a coin to automatically deliver a button, the checking and control of the feed of which is effected through the medium of the insertion 10 of the coin in the slot for passing thereof to the coin box or receptacle.

More particularly, this invention relates to 15 a novel casing for the coin controlled apparatus. This casing is generally rectangular in form and is provided with glass panes which are secured to the top and base thereof by novel locking means.

In cases of this sort, the glass panes are clamped between the top and bottom by 20 means of rods which were fastened to the top and bottom, respectively. The result is that all of the pressure of the rods comes upon the glass. To prevent the glass from breaking because of the great pressure which 25 is brought upon it, it is necessary to grind the edges carefully. A felt packing is generally used, but it is found that the felt soon becomes loose, even though it is originally glued in position.

To overcome the above difficulties, I have 30 provided a spring clip which is held by the clamping or through rods. Each leg of the clip has a slight bend which serves as a cushion underneath the glass. I also provide 35 in connection with this spring clip suitable corner angles of metal which serve to receive the pressure of the screw rods. In this way I avoid the necessity of grinding the edges of the glass and, at the same time, 40 relieve it of the pressure which would otherwise come upon it.

Now, in order to acquaint those skilled in 45 the art with the manner of constructing and operating a device according to my invention, I shall describe in connection with the accompanying drawings a specific embodiment of the invention.

In the drawings:—

Fig. 1 is a front elevation of my novel 50 casing for an automatic vending machine;

Fig. 2 is an enlarged sectional view there- 105 of showing the manner in which the glass is clamped between the base and the top plate;

Fig. 3 is an enlarged horizontal sectional view of my casing and shows the manner in 55 in which the spring clips are mounted to relieve the glass of pressure; and

Fig. 4 is an isometric view of a spring clip of my invention.

The coin control vending machine comprises generally, a case having a top portion in which are coin slots, the case being preferably of glass and the base being of cast metal or suitable material to retain the machine in an upright position and prevent the 60 same from tipping over, the base having a closed coin receptacle and an open compartment through which the merchandise is delivered. The top of the case is provided with means to cover a series of coin chutes 65 adapted to have a vertical reciprocating movement in the case and cooperating with the coin and actuating mechanism mounted on merchandise delivery hoppers or magazines also positioned in the case, which actuating or trigger mechanism is adapted to engage with a finger on the adjacent coin chute whereby on the dropping of a coin 70 through the coin slot and chute, the actuating mechanism, is operated to automatically deliver one piece of merchandise from the hopper to the open compartment in the base. Means are also provided in the actuating mechanism of the hopper to prevent fraudulent removal of the merchandise from the 75 hopper.

Referring to the drawings in detail, in 80 which like reference characters designate corresponding parts throughout the several views, the machine or apparatus includes 85 the base 10 of suitable size and weight provided with a merchandise delivery compartment or tray 11 open at the front, and a money compartment or coin receptacle 12 at the rear portion and divided therefrom by 90 the partition formation 13 extending transversely of the base. The base is preferably provided with cushion feet 14, which space the same from the supporting surface and at the top with a surrounding flange 15 receiving a case 16 thereon and adapted to house the actuating mechanism of the device. The case 16 is preferably of rectangular cross-section and includes glass panels or other transparencies 17 held in a suitable 100 frame including corner strips 18, extending

between a top plate 19 preferably of metal and a bottom frame 20 and constituting spacing means therefor and to prevent pressure on the glass panels when connected by the 5 corner rods or clamping bolts 21 through the medium of nuts 22 threaded on the lower ends thereof and provided with grooves 23 for engagement by locking levers 24 pivoted at 25 on bosses on the bottom of the base 10 shown. The locking levers 24 extend through a slot 26 and are provided with apertured ears 27 for engagement by a padlock to retain the case on the base and prevent access to the interior thereof.

15 Rods 28 are provided at opposite sides of the base adjacent to or in line with the pivot screws 25, which latter may form retainers therefor although said rods are preferably screwed into the base and have spacing 20 sleeves 29 mounted thereon to support and retain in position an angular bottom plate or partition 30 extending horizontally in spaced relation above the top of the base 10 and having a downwardly extending portion 25 or vertical part 31 engaging in front of the partition 13 to prevent access to the coin receptacle or compartment 12.

An angular top plate 32 is retained on the rods 28 between the headed upper ends thereof and the adjacent ends of the sleeves 29, and a cover 33 is provided thereon and clipped thereto, that is, provided with tongues engaging slots in the plate 32 at the opening in the top or cover plate 19 of the case, as indicated at 34 and projecting therein to render the fastening means of the cover inaccessible. The cover or hood 33 has a series of vertical coin slots 35 for the insertion of the coins which are designed to 30 pass into the chutes 36 arranged therebelow and having forwardly curved upper ends disposed through slots 37 in the plate 32 in the bottom of the hood or housing, closing the upper ends of the coin chutes 45 38.

Although any number of the coin slots and chutes may be provided, together with a corresponding number of article or button magazines or hoppers 45 as desired, six of such magazines or hoppers are shown in Fig. 1 of the drawings. These magazines are mounted between the plates 30 and 32, having suitable tongues entering slots therein as indicated at 46 and arranged at right angles to the coin chutes 36 at points intermediate their widths. The magazines or hoppers 45 are provided with front slots 47, the sheet material or metal of the magazines being bent so that the edges thereof are in spaced relation. This is done in order that the shanks of the buttons may project therethrough, as clearly shown on the drawings, the buttons or other articles to be dispensed by this check controlled apparatus being 60 designated at 48. Obviously, any articles 65

other than buttons, which will be accommodated in the magazines or hoppers, may be sold by the apparatus.

The trigger and operating mechanisms form no part of the present invention, and are described in detail in my co-pending application filed August 27, 1924, Serial No. 734,373.

Spring clips 50 which are provided with the angularly bent arm 51 are preferably 75 engaged upon the rods 21 by means of the openings 52. These clips are disposed between the bottom edges of the glass or transparent panels at the bottom frame 20 to take the clamping stresses and obviate the 80 necessity of having the glass ground on the edges and to take the pressure when the rods are tightened up instead of using felt packing, thereby preventing the glass from 85 breaking. In view of the bend on each leg 90 of the clip, a spring action is provided to give the necessary cushioning effect beneath the glass. This overcomes the difficulty experienced with felt, which when glued in position soon became loose, owing to the glue 95 drying out. The glass panels fit snug against the sides of merchandise magazines or hoppers 45 and in conjunction with the bottom plate or partition 30 and its vertical 100 wall 31, the escape of coin from the coin receptacle or the possibility of working the same between the panels and the hoppers and robbing of the machines, is prevented. Furthermore, the coins may be hidden from 105 view by means of a plate or baffle 53 of U-shaped construction which closes the back and sides of the coin receptacle above the top of the base 10 beneath the parts 30 and 31, the sides thereof being connected by cross-strip 54, if desired. Also, a lock 55 110 may be provided at the top, being mounted underneath the cover plate 19 to engage beneath the plate 32. This lock may be operated by a suitable key from the outside so that the bolt may be projected beneath 115 the plate 32 or retracted therefrom to permit the cover to be locked into position with the case, or removed for obtaining access to the coin receptacle and for refilling the hoppers or magazines, as well as repairs or 120 replacement of parts. The merchandise, such as the collar buttons 48, may be the article to be vended or boxes or inclosures containing the same, as it is thought will be 125 apparent.

I do not wish to be limited to the details shown or described.

I claim:—

1. In a vending machine, a base, and a case on the base adapted to house the holding and delivering mechanism of the machine, said case having top and bottom frame members and corner portions, spacing members between the top and bottom frame members and metallic washers having an 125 130

gularly bent leg portions mounted on the connecting members, said angularly bent leg portions adapted to engage beneath the edges of the panels of the case and a frame member to take the pressure on the panels.

2. In a vending machine, a base, a case mounted thereon, a top plate, frame members between the top plate and the bottom of the case, panels between the top and bottom frame members, means for drawing the top and bottom frame members toward the top and bottom edges of the panels, and spring washers between the bottom edges of the panels and the bottom frame member stamped from sheet metal with portions between the frame member and panels angularly bent, as and for the purposes described.
3. In a vending machine casing, a top plate, a base, panels confined between the top plate and the base, rods connecting the top plate and the base, means cooperating with
- 10
- 15
- 20

the rods for forcing the top plate and the base toward each other, and spring members carried by the rods and confined between the base and the panels, said spring members being placed under tension by the act of forcing the base and top plate toward each other.

4. In a vending machine casing, a top plate, a base, panels confined between the top plate and the base, rods connecting the top plate and the base, means cooperating with the rods for forcing the plate and the base toward each other, spring members having openings receiving the rods and provided with resilient offset arms disposed between the panels and the base, said arms resiliently resisting movement of the panels toward the base.

In witness whereof, I hereunto subscribe my name this 19 day of June, 1925.

JOHN G. WYNN.
